(57) **CLAIM**

The ornamental design for a hose reel, as shown and described.

DESCRIPTION

FIG. 1.1 is a top, front, left-side perspective view of a hose reel, showing my new design;

FIG. 1.2 is a top, rear, right-side perspective view thereof;

FIG. 1.3 is a top view thereof;

FIG. 1.4 is a right-side view thereof;

FIG. 1.5 is a front view thereof;

FIG. 1.6 is a left-side view thereof; and

FIG. 1.7 is a rear view thereof.

The broken lines depict portions of the hose reel that form no part of the claimed design.

1 Claim, 7 Drawing Sheets
